UNITED STATES PATENT OFFICE.

LOUIS STEINBERGER, OF BROOKLYN, NEW YORK.

INSULATED SUPPORT FOR ELECTRICAL CONDUCTORS.

1,342,312.

Specification of Letters Patent.

Patented June 1, 1920.

Application filed September 24, 1919. Serial No. 325,949.

To all whom it may concern:

Be it known that I, LOUIS STEINBERGER, a citizen of the United States, and a resident of the borough of Brooklyn, city and State of New York, have invented certain new and useful Improvements in Insulated Supports for Electrical Conductors, of which the following is a specification.

My invention relates to an improved insulated support for electrical conductors for high frequency and high tension currents. The structure is especially adapted for use in radio apparatus wherein the contact or slider is mounted to have a mechanical and consequently an electrical connection with the conductor coils.

One of the objects of my invention is to provide a hollow elongated body of insulating material having metallic strips forming helical coils secured at intervals to the inner and to the outer surface of the elongated body, the remaining portions of the metallic strips being exposed.

Another object of the invention is to provide a hollow elongated body of insulating material having conducting strips in the form of helical coils secured at intervals respectively to the outer surface and to the inner surface of the elongated body, the points of securing on the respective surfaces alternating with respect to each other.

Another object of the invention is to provide a hollow elongated body of insulating material, the outer surface of which is so shaped as to have a plurality of flat sides situated at angular positions with respect to each other, and the inner surface is also provided with similarly arranged flat sides in combination with strips of metal having the shape of helical coils, one of said strips being secured to the insulating material at intervals substantially at the center of the flat sides forming the inner surface, and the other strip being secured to the outer surface of the insulating body at the angles formed by the adjacent flat sides, ventilating spaces being formed between the said strips and the respective surfaces of the insulating body.

Other objects will appear from the subjoined specification and claims.

Referring to the drawings:

Figure 1 is a view in vertical section of a structure embodying one form of my invention, taken on line 1—1 of Fig. 3.

Fig. 2 is a view partly in vertical sec-

tion and partly in side elevation of a structure embodying another form of my invention.

Fig. 3 is a plan view of the structure shown either in Fig. 1 or Fig. 2.

Figs. 4 and 5 are fragmentary portions of the metal strips forming the coils.

The insulating material from which the body is formed may be of any suitable material for that purpose but it is preferred to use the insulating material which is well known in the art as "electrose", and the conductor is made of any suitable conducting metallic material, preferably copper.

The hollow elongated body of insulating material is provided with a plurality of flat surfaces longitudinally arranged thereupon, each flat surface being angularly situated with respect to its adjacent flat surface. The flat surfaces of the outer wall are parallel respectively to the flat surfaces of the inner wall and equal in number thereto. Thus arranged the horizontal cross section of the insulating body will be either triangular, rectangular, hexagonal, octagonal and so forth, or the flat surfaces constituting the side of the body may be either five, seven, nine, and so forth, in number, all as will be clearly understood.

I have chosen to illustrate in the figures of the drawing an elongated body provided with six pairs of flat surfaces constituting respectively the outer and the inner wall of the body, the shape of which in horizontal cross-section is hexagonal. This is deemed sufficient to clearly disclose my invention without unnecessarily multiplying the sheets of the drawings.

Referring to the drawings, 10 is a hollow body of insulating material, elongated in shape, the outer and inner walls thereof being formed respectively by the longitudinally arranged flat surfaces A, A'; B, B'; C, C'; D, D'; E, E'; and F, F'.

Metallic strips 12 and 12', each forming helical coils as shown, are secured respectively to the outer and inner walls of the hollow elongated body of insulating material. The outer strip 12 is secured at intervals to the angles formed by the intersection of the sides A and B, B and C, C and D, D and E, E and F, and F and A, and the inner coil 12' is secured to the surfaces A', B', C', D', E', and F' forming the inner wall of the insulating material.

The strips 12 and 12' may be secured re-

spectively to the outer and inner walls of the hollow body of insulating material so that the curve of one coil is coincident with the curve of the other coil, as clearly shown in Fig. 1, or the coils 12 and 12' may be alternately arranged with respect to each other, as shown in Fig. 2. It will be seen that spaces 15 are formed between the inner edge of the strip 12 and the flat sides forming 5 the outer wall, which openings may be utilized for ventilating and cooling purposes, and likewise for the same purpose spaces 16 are formed between the outer edge of the coil 12' and the angles formed by 10 the inner surfaces A', B', C', D', E', F' intersecting with each other.

In Figs. 4 and 5 I have illustrated holes 20 or roughened spaces 21 on the strips forming the coils, by means of which the 20 coils may be more effectively anchored or secured to the sides of the insulating body.

As stated above, the insulating body may be made of any approved insulating material, and when made of insulating material 25 which can be molded into the form desired, the helical conducting coils are secured or embedded into the insulating material during the process of molding. When the insulating body is made of fire-proof material, such as porcelain, the helical coil may be 30 secured to the insulating body by means of cement or other securing material, all as well understood in the art.

As will be seen, the structure described 35 may be so mounted that in use the contact or slider can revolve and travel up and down along the helix, the body of the insulator remaining stationary, or else the contact or slider can remain fixed and the elongated insulating body may rotate, so that 40 the metallic strip will remain always in contact with the slider. In this latter case the elongated body of insulating material as it rotates will move in the direction of 45 its axis.

As changes of construction could be made within the scope of my invention, it is intended that all matter contained in the above description or shown in the accompanying drawings shall be interpreted as 50 illustrative and not in a limiting sense.

Having thus described my invention what I claim as new and desire to secure by Letters Patent is:

55 1. As an article of manufacture, an elongated hollow body of insulating material, the outer and inner walls of which are provided respectively with flat sides extending longitudinally thereof, each side of each 60 wall being angularly situated with respect to its adjacent side in combination with helical conducting coils secured respectively to the outer wall and to the inner wall at points uniformly spaced apart, the remain-

ing portions of the coils being exposed to 65 form electrical contacts.

2. As an article of manufacture, an elongated hollow body of insulating material, the outer and inner walls of which are provided respectively with flat sides extending 70 longitudinally thereof, each side of each wall being angularly situated with respect to its adjacent side in combination with helical conducting coils secured respectively to the outer wall and to the inner wall at 75 points uniformly spaced apart, providing ventilating spaces between the coils and walls, the remaining portions of the coils being exposed to form electrical contacts.

3. As an article of manufacture, an elongated hollow body of insulating material, the outer and inner walls of which are provided respectively with flat sides extending longitudinally thereof, each side of each wall being angularly situated with respect 80 to its adjacent side in combination with helical conducting coils molded respectively to the outer wall and to the inner wall at points uniformly spaced apart, the remaining 85 portions of the coils being exposed to form electrical contacts.

4. As an article of manufacture, an elongated hollow body of insulating material, the outer and inner walls of which are provided respectively with flat sides extending 90 longitudinally thereof, each side of each wall being angularly situated with respect to its adjacent side in combination with helical conducting coils molded respectively to the outer wall and to the inner wall at 95 points uniformly spaced apart, forming ventilating openings between the respective coils and the walls to which they are secured, the remaining portions of the coils being exposed to form electrical contacts.

100 5. As an article of manufacture, an elongated hollow body of insulating material, the outer and inner walls of which are provided respectively with parallel flat sides extending longitudinally thereof, each side 105 of each wall being angularly situated with respect to its adjacent side in combination with helical conducting coils secured respectively to the outer and inner wall and alternately arranged with respect to each other.

110 6. As an article of manufacture, an elongated hollow body of insulating material, the outer and inner walls of which are provided respectively with parallel flat sides 115 extending longitudinally thereof, each side of each wall being angularly situated with respect to its adjacent side in combination with helical conducting coils secured respectively to the outer and inner wall at points 120 alternately arranged with respect to each other, both vertically and horizontally.

125 7. As an article of manufacture, an elong-

- gated hollow body of insulating material, the outer and inner walls of which are provided respectively with parallel flat sides extending longitudinally thereof, each side of 5 each wall being angularly situated with respect to its adjacent side in combination with helical conducting coils molded respectively to the outer and inner wall at points alternately arranged with respect to 10 each other, both vertically and horizontally.
8. As an article of manufacture, an elongated hollow body of insulating material, the outer and inner walls of which are provided respectively with parallel flat sides 15 extending longitudinally thereof, each side of each wall being angularly situated with respect to its adjacent side in combination with helical conducting coils secured respectively to the outer and inner wall at 20 points alternately arranged with respect to each other, providing ventilating spaces between the points of securement and the walls of the insulating body.
9. As an article of manufacture, an elongated hollow body of insulating material, the outer and inner walls of which are provided respectively with parallel flat sides extending longitudinally thereof, each flat side of each wall being angularly situated 25 with respect to its adjacent flat side in combination with helical conducting coils mold- 30 with respect to its adjacent flat side in combination with helical conducting coils mold-
- ed respectively to the outer wall at the angles formed by adjacent flat sides, and to the inner wall at points between the angles formed by the adjacent flat sides, forming 35 ventilating spaces between the respective coils and the respective walls to which they are attached, the remaining portions of the coils being exposed.
10. As an article of manufacture, an elongated hollow body of insulating material, the outer and inner walls of which are provided respectively with parallel flat sides extending longitudinally thereof, each flat side of each wall being angularly situated 40 with respect to its adjacent flat side in combination with helical conducting coils secured respectively to the outer wall at the angles formed by adjacent flat sides, and to the inner wall at points between the 45 angles formed by the adjacent flat sides, forming ventilating spaces between the respective coils and the respective walls to which they are attached.

In witness whereof I have hereunto set 55 my hand at the borough of Manhattan, city and State of New York, this 18 day of September, 1919.

LOUIS STEINBERGER.

In presence of—
ZITA M. GRAHAM.
